MERCURY TUBE SWITCH

*Joseph H. Staley, Columbus, Ind.

Application January 29, 1934, Serial No. 708,844
Renewed March 13, 1937

6 Claims. (Cl. 200—152)

Reference is made to my application Serial No. 667,323 filed April 1933, for which this application is substituted and also to my Patent No. 1,906,118 issued April 25, 1933.

5 This invention relates to the art of electric switches and particularly to that type of switch which employs a fluid medium to form a connection or bridge between two electrodes within an envelope. A primary object of the invention 10 is to provide means for quenching the arc which arises upon breaking a circuit through flow of the bridging medium.

A further primary object of my invention is 15 to provide means for controlling the location of the arc so that it will not pit or otherwise damage switch parts but will always be located over a medium which is substantially non-deteriorating under the influence of the arc. This control of the position of the arc is highly essential in 20 order to prevent the arc from affecting exposed metal or other surfaces so as to prevent contaminating of the fluid with the material of the metal or of such surfaces.

An important advantage of my invention is 25 that it may be embodied in a structure having a metallic envelope, parts of which serve directly as electrodes whereby the usual difficulty encountered in employing fragile envelopes is eliminated.

A further important object of my invention is 30 to provide sealing means in a two part envelope so as to prevent the admittance of atmospheric air and also to prevent the escape of the gas which may be used to fill the envelope. This sealing means is particularly important when the invention is to be incorporated in a metallic envelope.

The fluid herein referred to as a suitable medium for providing a bridge between electrodes is preferably mercury and many problems arise 40 when mercury is employed in direct contact with a metallic envelope. If the bridge of mercury between two parts of the envelope is separated in breaking a circuit to have the arc occur directly on or over the metallic surface of the envelope, pitting or deterioration of the envelope would generally occur with the result that the material thereby removed is taken up by the mercury so that the mercury will then have a 45 different behavior than it has when in a free state. In order to effectively break a circuit through flow of mercury, it is highly important that the mercury be maintained in such a state that there are no impurities introduced which 50 would cause the mercury to string out and leave

conducting paths after the principal flow of the mercury.

I find that if the arc occurring upon the break of the mercury bridge is quickly quenched and is controlled in location so as to occur over an insulated or rather refractory surface removed from the wall of the envelope, whether it be metal, glass, or otherwise, a dependable switch may be had, depending of course upon the employment of an adequate sealing means to prevent atmospheric gases from passing within the envelope and preventing, when employed, inner gases in the envelope from escaping. 5

A further important object of my invention is 10 to provide means for quenching an arc within the envelope which are automatic in operation and are made effective by the arc or flow of current itself so that no moving parts are required. 15

While my invention is preferably intended to 20 employ a metallic envelope, it may be embodied in envelopes of glass, Bakelite and the like although such envelopes present the objections of being fragile and of requiring electrodes to be passed and sealed through the envelope whereas the metallic envelope may be formed to be utilized directly as the electrodes. The foregoing 25 objects and advantages as well as many others will become apparent to those versed in the art in the following description of the invention which is made in reference to the accompanying drawings, wherein 30

Like characters of reference indicate like parts 25 through the several views in the drawings.

Referring first to the preferred form of my invention wherein a metallic envelope is employed, reference is made to Figs. 1-16 in the accompanying drawings. I form a tubular body 10 made from metal closed across one end by a metallic wall and open at the other. I have used a wide variety of metals including iron, and various alloys, one of which is commercially known as "stainless" steel. The essential characteristics of the metal to be employed are that it be non-amalgamating with mercury and preferably not wetted by the mercury. The external diameter of the body 10 adjacent its open end is reduced so as to receive thereover an insulating bushing 11. A metallic cap 12 is formed to have an internal bore adapted to receive the bushing 11 therewithin so that the cap may be fitted about the bushing in telescoping relation with the body 10. The bushing 11 and cap 12 each have a length greater than the length of the reduced diameter portion of the body 10. A refractory member 13, hereinafter referred to as a breaker, has an external cylindrical surface formed to fit snugly within the bushing 11 between the open end of the body 10 and the closed end of the cap 12. This breaker 13 may be made in a number of different forms such as the form 13' in Figs. 1-7, 13 in Figs. 8-11, and 13'' in Figs. 12 and 13.

The breaker 13' in Figs. 1-7 is formed to have a cylindrical bore 14 centrally disposed about the longitudinal axis of the body and cap and in that end of the breaker toward the closed cap end. The bore then flares outwardly from this 60 cylindrical shape to form the conical bore 15 flaring out to a diameter equal to that of the internal diameter of the body 10.

The breaker 13 as shown in Figs. 8-11 is formed to have a short cylindrical bore centrally disposed about the longitudinal axis of the envelope formed by the body 10 and the cap 12 with the intervening bushing 11. The bushing 13 is formed to have an annular lip 16 projecting toward the cap 12. On the other side of the breaker 13 there is provided a counter-bore 17 having a diameter substantially equal to that of the internal diameter of the body 10, the counter-bore 17 forming a right angle shoulder between it and the bore of reduced diameter. The 70 breaker 13'' shown in Figs. 12 and 13 is in effect 75

a circular disk having a central longitudinal bore therethrough.

Regardless of the particular formation of the breaker, it is compressively carried within the end of the bushing 11 so as to be separated by 5 the bushing from direct contact with the cap 12, this particular combination being shown by my Patent No. 1,906,118, issued April 25, 1933. The insulating bushing 11 is made of substantially non-deteriorating material which may be sufficiently resilient to permit its being used between the body 10 and the cap 12 and over the breaker 13 to give a pressed fit. The bushing 11 may be made of Bakelite, rubber, casein, wood fiber, and synthetic compositions having similar 10 properties. One particular material suitable for this purpose is a vulcanized fiber composed of approximately 93 per cent cellulose and cellulose derivatives, 6 per cent water, and 1 per cent ash. It is of course desirable to employ a material 15 that will not become affected by exposure to air. The breaker 13 is preferably made out of some material which will withstand the intense heat of an arc. A number of refractory materials are available such as soap stone, lava and fused 20 silica mixtures, one of which mixtures has as its principal ingredients in approximate proportions silica 49.97 per cent; magnesia 44.62 per cent; and iron 3.44 per cent. This mixture is fused at approximately 2000° F. and is hard but 25 may be broken under heavy impacts. The breaker 13 made of this or some other suitable refractory material is resiliently supported within the bushing 11 and thereby spaced from the enveloping wall of the cap 12. 35

A quantity of mercury 18 is carried within the envelope from which air has been exhausted and preferably replaced by an inert gas, hydrogen gas being classed as inert and indicated for the purpose on account of its low cost. Other gases, 40 such as nitrogen and helium may be used. The air may be exhausted and replaced by the gas to be employed by any suitable means, one particular form being shown by my Patent No. 1,895,177, issued Jan. 24, 1933.

In the form shown in Figs. 8-10, the bushing 11 and the cap 12 have suitable lengths so that when the breaker 13 is placed in the bushing 11 to have its face flush with the end of the bushing, there is a short gap between the counter-bored end of the breaker and the open end of the body 10 in which the bushing 11 is exposed. This gap provides an annular groove between the breaker and the body. When the tube is tilted to the position as indicated in Fig. 8, the 55 mercury will bridge across and through the breaker 13 to interconnect the body 10 and the cap 12, thereby establishing an electrical connection therebetween. The bore through the breaker 13 is made to have a diameter defining a 60 "neck" of mercury therethrough of a cross-sectional area which will carry without undue heating the flow of current for which the switch is rated. 55

Now when the tube is tilted back toward the 65 horizontal position as indicated in Fig. 9, the mercury 18 will tend to assume the positions indicated wherein the mercury breaks within the bore of the breaker 13 to leave a quantity within the small chamber which exists between the breaker 13 and the end of the cap 12. The major portion of the mercury will be on the body side 70 of the breaker. Further tilting of the tube to some such position as indicated in Fig. 10 will cause the main portion of the mercury which is 75

on the body side of the breaker 13 to flow on down into the body 10 as indicated. A small globule of mercury 19 will be left within the groove between the breaker and the body end. The 5 globule 19 is provided so that there will always be mercury at the end of the body so as to protect that end. Particular attention is directed to the location of the breaker 13 in reference to the end of the cap 12. One important factor of 10 this location is that the small chamber formed therebetween be so shaped and so proportioned that a globule 20 of mercury will always remain in that chamber when the tube is rocked from the closed to the open circuit positions and further- 15 more that once the bridge of mercury has been broken as indicated in Fig. 9, further tilting of the tube will not cause any more mercury to spill over from the globule 20 through the breaker to join the main mass. This "after" spilling is to be 20 avoided so that there is no tendency to reestablish the circuit in any event and particularly through a small stream of the mercury since such reestablishment would cause a "flicker" in a lamp circuit and moreover would have a tendency to 25 produce heat within the tube by reason of the fact that this small stream would be insufficient in cross-sectional area to carry the current with the result arcing would occur at some point, the location of which would be difficult to control. 30 Not only is it extremely important to properly proportion the small chamber as indicated, but it is of the utmost importance to bring the end of the cap 12 sufficiently close to the central bore through the breaker 13 as to establish what is 35 considered to be a "rebound" wall or a baffle so that pressures of mercury vapor and gases, suddenly created by an arc between the globule 20 and the main mass of the mercury 18, within the breaker bore will be prevented from becoming 40 dissipated in the direction toward the cap and will be so controlled as to cause the effective reduction of the pressure to be through the other end of the breaker bore directed toward the larger opening within the body 10. The structure 45 is so designed as to produce a blast or quick flow of the gases through the arcing zone into the larger chamber so as to quench the arc. 50 The smallest distance that the end of the cap may be spaced from the bore through the breaker 13 is zero and this would be most effective were it not for the fact that the interruption of the current would then be not between two masses of mercury but between mercury and the metal 55 wall of the cap exposed across the end of the breaker bore. It is possible that this exposed surface could be made of a suitable alloy so as to resist burning or pitting action of the arc. This would be effective for relatively small flows of current but where higher flows are to be 60 interrupted, it is much more desirable to interrupt the flow between two masses of mercury. Hence it becomes necessary in many cases to space the cap end a slight distance away from the breaker bore. The greater this distance is the less effective 65 is the arc quenching action of the tube as may be readily seen from the fact that were the breaker to be placed out, for example, midway between the cap and body ends, the pressure would be dissipated equally in both directions 70 without producing any particular flow across the central arcing area. It is therefore believed to be necessary to keep the breaker sufficiently close to some wall as will cause the resultant flow of gases to be away from that wall through the ar- 75 ing area and into a larger chamber.

For the particular type of construction illustrated in Figs. 8-10, I find that for a conservative capacity of 15 amperes, the cylindrical bore through the breaker 13 may be $\frac{1}{2}$ inches in diameter and that the distance between the lip 16 5 and the inside face of the end of the cap 12 is $\frac{1}{8}$ inches. The lip itself projects $\frac{1}{16}$ inches from the end of the breaker. The internal diameter of the cap between the breaker and the cap end is $3\frac{5}{64}$ inches. The length of the cylindrical bore 10 in the breaker is $\frac{3}{8}$ inches; diameter of counter-bore $\frac{1}{2}$ inches; length of counter-bore $\frac{1}{2}$ inches; internal diameter of the bushing 11, $\frac{1}{2}$ inches; distance between the breaker 13 and the body 10, $\frac{1}{8}$ inches; internal diameter of the body 10, $\frac{11}{16}$ inches; and internal length of the body 10, $1\frac{1}{8}$ inches. It is understood that these dimensions are given as one particular proportion and that the invention is not limited thereto. For the switch tube, a safe rated capacity is 15 amperes 20 at 50 breaks per minute within a 40 degree C. temperature rise, at 110 volts.

The purpose of the lip 16 extending into the chamber between the breaker and the cap end is to entrap mercury within that chamber so that 25 there will always be retained the globule 20 therein even though the tube may have been turned entirely up on end with the body 10 lowermost before the circuit is made. This lip also serves to prevent "after spill" following the breaking 30 of the bridge of mercury. Further, this lip permits the provision of a chamber adequate to retain sufficient mercury for the rated current capacity in contact with the cap and at the same time permitting the end of the cap to be brought 35 relatively close to the end of the breaker across the bore therein.

By reason of the peculiar construction above set forth, several very desirable qualities are obtained. The tube having a metallic envelope 40 made of metal is non-breakable. A seal between the body and cap is obtained through the medium of the intervening insulating bushing 11. In addition to the sealing and insulating properties of the bushing 11, there is the additional feature 45 of the cushion afforded to the breaker 13 against blows or impacts received by the metallic wall. The tube being gas filled with some inert gas such as hydrogen prevents any oxidation from occurring as might be induced by the arc occurring 50 between the two mercury bodies. The particular formation of the breaker 13 is such that it mechanically tends to separate the main mass of mercury 18 to leave the globule 20 in the small chamber in the cap end without "after spill". 55 The sharp shoulder at the body end of the cylindrical bore in the breaker 13 cuts up through the body of mercury 18 relatively to aid the mercury, through its inherently great surface tension and cohesion, to separate and withdraw from the 60 globule 20 into the larger mass in the body. Should for any reason the arc follow the larger body of mercury toward the end of the body 10, there is always the globule 19 left to be the last 65 part of the body electrode so that the arc would not occur in direct contact with the end of the body 10. Again it is to be noted that the separation of the mercury into the globule and main body takes place directly within the small cylindrical bore of the breaker 13, Fig. 9, so that the 70 arc is within this comparatively confined space.

The location of the breaker in the envelope and the diameter of the breaker bore are preferably made to be such that the cross-sectional area of the mercury bridge is not less than half 75

of the cross-sectional area of the bore at the instant of breaking of the bridge, the ideal condition being to maintain that cross-sectional area of the bridge substantially equal to the cross-sectional area of the breaker bore at the instant of breaking.

The switch in the forms above and hereinafter described is characterized by long life under severe service conditions. The successful operation of the switch is believed to be due to several factors, namely, first, a confined arcing zone having a turbulence therein; second, a gas blast through the arcing zone; third, a wall substantially confining the arcing zone such that the arc is in intimate contact for a major portion thereof; fourth, the temperature in the arcing zone is rapidly reduced; fifth, the mercury bridge is magnetically pinched to accelerate the breaking of the bridge; and sixth, the mercury bridge just prior to breaking is magnetically lifted to stretch it and accelerate its breaking. These factors and their effect upon quenching the arc arising upon breaking of the mercury bridge are believed to operate as will now be described.

At the moment of arcing, the space therearound becomes highly ionized and there is an added degree of mercury vaporization. This vaporization plus the expansion of the vapor and the gas due to the heat of the arc, sets up a pressure about the arc within the cylindrical bore which of course tends to dissipate itself in all directions. Being confined circumferentially within the breaker, there are but two directions in which the pressure may dissipate, one toward the body 10 and the other toward the end of the cap 12. There being nothing to hinder the expansion of the gas into the body 10, there is a flow accordingly in that direction. This is further emphasized by the gas attempting to travel in the other direction and striking the cap and so as to cause a "rebound" in effect therefrom to follow up the flow of gas toward the body and thereby accelerating that flow so that the net result is to cause a blast through the cylindrical bore of the breaker 13 across the arcing zone into the body 10. This blast very effectively aids in quenching the arc since the highly ionized charges are carried away from the arcing zone to prevent reestablishment of the arc and the path of the arc itself is tended to be distorted and lengthened to increase the resistance thereof. The end wall of the cap 12 may be considered to be in effect a baffle which prevents the dissipation of the arc induced pressure from the breaker theretoward and the body 10 may be considered to be a dissipating chamber into which the pressure is dissipated and reduced by reason of its comparatively large volume and cooling effect.

In addition to this "gas blast", it is to be noted that the bore in the breaker is of that size whereby the arc occurring therein is closely confined or surrounded to the end that the occurrence of the arc sets up a great degree of turbulence in that confining space such that the contents are greatly agitated and mixed all tending to aid in deionization of the space charge. Also, to be considered, is the fact that the wall of the breaker bore either by its cylindrical surface or the sharp shoulder at the end, or both, actually intrudes into the arc when it occurs, which element again aids in deionization of the arcing zone.

Heat is also rapidly dissipated by the movement in the breaker bore and radiated through the metallic walls of the envelope. In addition to the gas blast effect, the intruding surface, the

turbulence, and the heat dissipation, there is the further "pinching" effect on the bridge of mercury by reason of the metallic wall of the cap 12 concentrically surrounding the cylindrical bore through the breaker 13. As the tube is tilted from the position indicated in Fig. 8 to that in Fig. 9, the tendency, by reason of the shape of the breaker 13, is to reduce the cross-sectional area of the mercury directly within the cylindrical bore of the breaker. Immediately there is any reduction in this cross-sectional area, the magnetic field concentrated in the surrounding metallic wall of the cap tends to further reduce this neck of mercury in the cylindrical bore by reason of the concentrated magnetic flux.

This "pinching" effect is set up by the field induced by the flow of current through the mercury bridge itself and is in addition to the severing action caused by the tilting of the tube to cause the mercury to flow over the breaker 13. The combined effect of the "pinching" action plus the mechanically cutting in two of the mercury products a "snap" action of the mercury causing a very quick separation so that this action in itself tends to keep the arc at a minimum.

Further advantage is taken of the magnetic field concentrated in the concentrically surrounding metallic ring in that as the "neck" is reduced by tilting the tube, the neck is then at one side of the bore, eccentric of its axis, and the field being then eccentric of the neck tends to pull that "neck" back up into the axis of the field, thereby tending to stretch that "neck" to aid in its severance by the "pull" of the mercury masses on either end. Also the eccentric field tends to stretch or curve the arc between the separating mercury masses upwardly to the center of the field.

Referring to Figs. 12 and 13, the breaker 13" is reduced to a disk form and the same properties as above indicated are embodied, particularly as to the turbulence, the gas blast, and the "snap" action due to the combined effect of the "pinching" by the magnetic field and the tilting of the tube to cut the mercury over the breaker. It is to be noted that the breaker 13" is resiliently carried by the bushing 11 as before. In Fig. 13, the breaker 13" is shown as being placed directly against the end of the cap 12, the cap 12 being in this case shortened sufficiently so as to reduce the chamber between the cap end and the breaker to zero, this giving the zero chamber as referred to above wherein the gas blast would be the maximum.

Referring now to Figs. 14, 15 and 16, the same type of construction is shown as appears in Figs. 8-11. In addition thereto there is indicated a particular means of additionally sealing the joint between the body 10 and the cap 12. This sealing means comprises a groove 21 circumferentially cut about the body 10 on that surface fitting within the bushing 11; a groove 22 cut circumferentially around the outer side of the bushing 11 at a distance removed from the groove 21 toward the open body end; and mercury or some semi-solid material in both of the grooves 21 and 22. The groove 21 is covered over by the bushing 11 and the groove 22 is covered over by the cap 12 so that the material within the grooves is retained. These grooves filled with a semi-solid material prevent seepage of gases thereacross in either direction, either from the atmosphere or from within the tube. I find that it is extremely important to effect a seal that will remain gas tight otherwise the tube soon becomes

inoperative. Mercury may be placed in the grooves 21 and 22 by submerging the body 10 in a bath of mercury sufficiently deep to come up and fill the groove 22, and while submerged to that depth, the cap 12 and bushing 11 are pressed over the body end.

Attention is now directed to the structure as shown in Figs. 1-6 wherein the only difference in structure over that shown in Figs. 8-13 is in the breaker 13'. In this form, the breaker 13' as above indicated has the short bore 14 which corresponds to the cylindrical bore in the breaker 13 above described and it is within this bore 14 that it is desired that the arcing if any occurs. The breaker 13' permits the same magnetic "pinching" and lifting effects on the bridge or neck of mercury by reason of the encircling band of metal of the cap and also provides for the gas blast to aid in quenching the arc. In the form as shown in Fig. 7, the breaker 13' is carried directly in contact with the end of the cap 12 to obtain the zero chamber therebetween corresponding to that above referred to.

Dimensions for one workable size of the structure indicated in Figs. 1-6 are as follows. For a tube switch having a rated capacity the same as of the structure first described, I form the body 10 to have an internal diameter of $\frac{1}{4}$ inch and a length including that of the breaker of $1\frac{1}{8}$ inches. The small chamber between the breaker and the cap end has a length of $\frac{1}{8}$ inch and a diameter of $\frac{7}{16}$ inch. The diameter of the cylindrical bore 14 in the breaker is $\frac{1}{8}$ inch. The small chamber has a depth of $\frac{1}{8}$ inch below the bore.

In either form of the invention above described, some suitable mounting means is provided, one particular form being here shown in Figs. 1-3 wherein a base 23 is provided to carry spaced apart clips 24 and 25, one set of clips being insulated from the other and both being adapted to receive the tube while therebetween. That is, the body 10 will be placed between one set of clips such as the clip 24 and the cap 12 would be pressed between the other clip 25. The clips 24 and 25 are then placed in the electrical circuit to be closed and opened.

While I have above indicated preferred forms of my invention as employing metallic envelopes, the invention may well be incorporated in a glass envelope, one particular form being shown in Figs. 17 and 18 as an example. In this form a glass envelope 26 is formed to have an electrode 27 sealed therethrough and projecting into a well 28. One end of the envelope 26 is sealed as at 29 and the other end has an electrode 30 carried therethrough in sealed relation, here shown as having a body of metal 31 within the tube forming a wall by its face across that end of the tube. A small chamber is left immediately in front of this electrode 30 by restricting the walls of the envelope 26 to form a bore 32 from which the walls slope outwardly into the envelope proper. This form is, insofar as setting up a gas blast is concerned, the same as that shown in Figs. 1-6. The envelope 26, by being formed to have the chamber between the bore 32 and the electrode 30, gives the same effect and the same formation as is found in the structure in Figs. 1-6 by employment of the breaker 13'. In the glass envelope form, the globule 20 remains in the chamber in contact with the electrode 30 and the main mass of mercury 18 separates therefrom in the bore 32 so as to have the arc occur substantially within the bore 32 thereby setting up

the gas blast the same as occurs within the metallic envelope form shown in Figs. 1-6.

In Fig. 19 is shown a further modified form of glass envelope wherein the bore between the main part of the envelope and the chamber immediately adjacent the end electrode is sufficiently extended as to define a cylindrical bore of appreciable length. In this form, the arc is more positively controlled and located to be within the bore. The "turbulent" effect is had within that cylindrical bore by the close confining of the arc, which includes the arc "intruding" surface.

In Fig. 20 is shown substantially the same type of structure as that in Fig. 19 with the addition of a metallic band 33 encircling the cylindrical bore 34 of the envelope. This band 33 is added as a means of concentrating the magnetic flux set up about the mercury bridge so as to accelerate by the "pinching" and the "lifting" action the severance of the mercury bridge or neck 20 as the tube may be tilted. Of course it is to be appreciated that in the forms of glass envelope shown in Figs. 17-20, the envelope must be mounted always to have the electrode 27 hang downwardly so that these particular forms 25 may not be mounted in any other axially rotated positions as may be the case with the metallic tubes above described.

In Fig. 21 is shown a still further modified form of a structure in which all of the above indicated arc controls may be utilized in quenching the arc. In this form, a glass envelope 35 is formed to have a main body from which a neck 36 is extended to have abrupt shoulders between it and the body. Electrodes 37 and 38 are sealed through the end of the neck 36 to enter therewithin and mercury 39 is employed within the envelope to bridge across the inner ends of electrodes 37 and 38 when the tube is tilted to raise the body end. A breaker 41 is employed to protect the glass wall and to "confine" the arc, circumferentially. In addition, a metallic ring 40 may be employed to encircle the neck as indicated so that the magnetic field set up by flow of current through the bridge of mercury between the electrodes may aid in severing the mercury by the "pinching" and "lifting" effects. The arc will occur between the ends of the electrodes within the relatively small bore of the neck 36 so that the gas blast will flow across this arcing position into the body of the envelope.

To summarize, by my invention, whether it be applied to a metallic envelope or to a glass or other non-conducting envelope, it is primarily my object to provide in a mercury tube switch, that feature of providing an arc confining wall to have at least part of that wall actually intrude or extend into the arc, and further to so confine the arc that by reason of the restricted arcing space, a turbulence is produced in that space; that feature of a blast of gas or vapor through the arcing space; that feature of dissipating heat from the arcing space; that feature of utilizing the field induced by the current flow through the switch to reduce the cross-sectional area of the mercury bridge; and that feature of also utilizing that field to lift and stretch that bridge to aid in breaking it, all of said features occurring automatically and substantially simultaneously to the end that the arc, as may arise upon the breaking of the mercury bridge, may be quickly quenched, principally it is believed, by deionization.

While I have herein shown and described my invention in the forms as now best known to me, it is obvious that structural variations may be

employed without departing from the spirit of the invention and I, therefore, do not desire to be limited to those precise forms beyond the limitations as may be imposed by the following 5 claims.

I claim:

1. A mercury switch comprising a metallic tubular envelope closed at each end and formed by two partially overlapping, magnetizable but 10 electrically separate parts and each part forming an electrode, a quantity of mercury flowable longitudinally within the envelope, and means adjacent one of the electrodes restricting the cross-sectional area of the column of mercury when 15 bridging said electrodes, the said restricting means being arranged between said one electrode and the overlapping zone of said parts, whereby an intensified magnetic field is set up adjacent 20 said restricting means promoting movement of the mercury therefrom by current flow in the mercury.

2. A mercury switch comprising a metallic tubular envelope closed at each end and formed by two partially overlapping magnetizable but 25 electrically separate parts and each part forming an electrode, a quantity of mercury flowable longitudinally within the envelope, and means adjacent one of the electrodes restricting the cross-sectional area of the column of mercury 30 when bridging said electrodes, the said restricting means being arranged between said one electrode and the overlapping zone of said parts, whereby an intensified magnetic field is set up adjacent 35 said restricting means promoting movement of the mercury therefrom by current flow in the mercury, the electrode part toward which the mercury flows upon breaking said bridge having less diameter than that of the other electrode.

3. A mercury switch comprising a metallic tubular envelope closed at each end and formed 40 by two electrically separate parts, each part forming an electrode, a quantity of mercury within the envelope flowably bridging the electrodes, and means restricting the cross-sectional area of the column of mercury bridging the electrodes, the 45 said restricting means being located adjacent one of the electrodes and the other electrode being magnetizable and having a smaller internal diameter than that of the said one electrode, where-

by a severing zone in said column is created by said means and an intensified magnetic field is created adjacent said zone tending to move the column therefrom.

4. In a mercury tube switch, a closed-end envelope, a pair of electrodes, a quantity of mercury bridgeable between the electrodes, means for restricting the cross-sectional area of the mercury bridge between said electrodes, and means concentrating a magnetic field induced by current flow through said mercury tending to move the mercury through said restricting means and toward one of the electrodes, said moving of the mercury being normally prevented by gravitational pull on the mercury maintaining said bridge through said restricting means when the switch is rocked to a closed circuit position, said one electrode comprising a mass of magnetizable metal, the cross-sectional area of which exceeds 20 that of the other electrode.

5. A mercury tube switch comprising in combination, a gas filled metallic tubular envelope closed at both ends and formed by two partially overlapping, magnetizable but electrically separate parts each forming an electrode, a quantity of mercury in the envelope shiftable to bridge said electrodes, means adjacent one of said electrodes restricting the cross-sectional area of said bridge, the relationship of the diameter of said area and the maximum spacing of said means 30 from said electrode being on the order of not exceeding approximately 1 $\frac{1}{4}$ to one.

6. A mercury tube switch comprising in combination, a gas filled metallic envelope closed at both ends and formed by two partially overlapping magnetizable but electrically separate parts each forming an electrode, a quantity of mercury in the envelope shiftable to bridge said electrodes, means adjacent one of said electrodes restricting the cross-sectional area of said bridge, the relationship of the diameter of said area and the maximum spacing of said means from said electrode being on the order of not exceeding approximately 1 $\frac{1}{4}$ to one, said means maintaining said restricted area for a length not exceeding approximately three-fourths of the diameter 40 thereof.

JOSEPH H. STALEY.
